ARMCHAIR

Cesare Cassina, Carimate, Italy, assignor to Centro Cassina S.r.l., Copreno di Lentate sul Seveso, Milan, Italy

Filed Feb. 5, 1974, Ser. No. 440,129

Claims priority, application Italy Aug. 30, 1973

Term of patent 14 years

Int. Cl. D6—01

U.S. Cl. D6—71

FIG. 1

FIG. 2

FIG. 3

FIG. 4

FIG. 5

FIG. 6

FIG. 1 is a front elevational view of the armchair of my new design;

FIG. 2 is a rear elevational view thereof;

FIG. 3 is a top plan view thereof;

FIG. 4 is a bottom plan view thereof;

FIG. 5 is a side elevational view; and

FIG. 6 is a vertical sectional view.

The side not shown in FIG. 5 is a mirror image of the side shown.

I claim:

The ornamental design for an armchair, as shown and described.
